UNITED STATES PATENT OFFICE.

HERBERT E. WHITE, OF YOUNGSTOWN, OHIO, ASSIGNOR TO THE GENERAL FIREPROOF-
ING COMPANY, OF YOUNGSTOWN, OHIO, A CORPORATION OF OHIO.

CLIP FOR FASTENING CERTAIN FORMS OF METALLIC LATHING TO BEAMS, GIRDERS,
AND THE LIKE IN BUILDING CONSTRUCTION.

1,075,802.

Specification of Letters Patent.

Patented Oct. 14, 1913.

Application filed January 31, 1912. Serial No. 674,621.

To all whom it may concern:

Be it known that I, HERBERT E. WHITE, a citizen of the United States, residing in Youngstown, county of Mahoning, State of Ohio, have invented a new and useful Improvement in Clips for Fastening Certain Forms of Metallic Lathing to Beams, Girders, and the like in Building Construction.

My invention relates to a spring device adapted to serve as a clip, and the object of it is to provide a simple and economical fastening especially adapted for attaching a sheet of metallic lathing to the edge portion of a flange when the edge of the flange and the superficies of the lath are at right angles or substantially so.

My clip is especially adapted to fastening combined lathing and furring sheets, such as is shown in United States Patent No. 1,008,877, granted to me November 14, 1911.

In the illustrations which are a part of this specification, like reference characters, refer to the same parts in different figures.

Figure 1 is a view in perspective showing the manner in which the clip engages the edge of a flange and the lath, and fastens the two together. Fig. 2 is a drawing of my clip showing how it is formed. Fig. 3 is a drawing substantially at right angles to Fig. 2, further illustrating the manner in which the clip is formed. Fig. 4 is a rear elevation. Fig. 5 is a side elevation.

My clip operates on the principle of a spring, and it is in fact a spring of novel form. As Fig. 2 shows it consists of a piece of furated steel, having the prongs bent to form hooks H, and the other end bent to form a double set of jaws J and J' connected integrally by the portion C. Any person skilled in the manipulation of metal to make springs, will understand from the drawings how to make the clip. The material used should be hardened steel of resiliency, suitable for springs.

It will be noticed in Fig. 2 that the clip is provided with notches or teeth T which serve to increase the frictional engagement of the jaws J. These are a desirable but not necessary feature.

In applying the clip as shown in Fig. 1, the lower portion F is adjusted on the edge of the support f adjacent the rib R of the lath, so that the hook portion H of the clip will be directly above the said rib. When the clip is in this position a blow from a hammer on the shoulder S will cause the jaws J to open at F and slip down and grip the flange f. At the same time the hook portion H will go down over the top of the rib of the lath and the pressure of the spring on the flange will serve to hold the several parts tightly together.

What I claim and desire to secure by Letters Patent is:

A clip adapted to fasten a high ribbed lathing structure to a beam or other support in building construction, the said clip being composed of a piece of wire or narrow strip of metal bent double, the free end portions being still further bent to form a hook adapted to engage the crown of the lath rib, the opposite end of the clip being turned up to form a set of double jaws having on each of their sides two substantially parallel clamping members, the outer clamping members of both sides terminating in a spring acting crown portion formed by the aforesaid bending of the metal double and the inner clamping members of both sides terminating in the portion that engages the rib of the lath.

In testimony whereof I affix my signature in the presence of two witnesses.

HERBERT E. WHITE.
